(57) CLAIM

The ornamental design for a cover for an exercise equipment handle, as shown and described.

DESCRIPTION

FIG. 1 is a top perspective view of the cover for an exercise equipment handle showing my new design;

FIG. 2 is a bottom perspective view thereof;

FIG. 3 is an elevation view thereof;

FIG. 4 is a top plan view thereof;

FIG. 5 is a bottom plan view thereof; and,

FIG. 6 is a perspective view of the cover for an exercise equipment handle in the environment of use thereof.

The broken lines showing the exercise equipment in FIG. 6 are included for the purpose of illustrating environment and form no part of the claimed design.

1 Claim, 5 Drawing Sheets
